UNITED STATES PATENT OFFICE.

THOMAS L. STURTEVANT, OF QUINCY, MASSACHUSETTS, ASSIGNOR TO STURTEVANT MILL COMPANY, OF BOSTON, MASSACHUSETTS, A CORPORATION OF MASSACHUSETTS.

SCREEN-SEPARATOR.

1,397,339.

Specification of Letters Patent.

Patented Nov. 15, 1921.

Application filed July 22, 1920. Serial No. 398,345.

To all whom it may concern:

Be it known that I, THOMAS L. STURTEVANT, a citizen of the United States, residing at Quincy, in the county of Norfolk and 5 State of Massachusetts, have invented an Improvement in Screen-Separators, of which the following description, in connection with the accompanying drawings, is a specification, like characters on the drawings representing like parts.

The invention to be hereinafter described relates to screen separators for grading materials.

These separators may be employed for 15 grading a great variety of materials to varying degrees of fineness. In some instances it is desirable to employ screen clothing of very fine mesh, usually of woven bronze wires of relatively small tensile strength 20 as compared to steel wires. It has been customary to stretch the clothing on its frame so as to cause the same to lie in flat, taut condition, but it is impossible to stretch the clothing without elongating the 25 wires more or less with resultant enlargement of the meshes or openings in the clothing. As a consequence, when materials are graded, they are not reduced to the fineness intended to be obtained by the clothing. 30 Also, certain materials graded are of a heavy character, and the mass thereof passing over the clothing is so great that the clothing is required to support heavy weights of materials which are liable to cause the clothing 35 to sag and become further stretched.

One of the purposes of the present invention, therefore, is to provide means for supporting the screen clothing in a manner such that it is unnecessary to tension the wires 40 of the clothing, but, on the contrary, the clothing may rest upon the supporting means in flat but unstretched condition.

It is desirable that the screen clothing shall be vigorously vibrated so as to maintain the meshes thereof in open condition 45 for efficient grading effect. Another purpose of the invention, therefore, is to provide a support or means beneath the clothing which will have a strong, sturdy character 50 efficiently to support the weight of the materials on the clothing, but at the same time of a resilient character such that it may be susceptible of lively vibratory movement, and vigorously thump or flap against the

clothing and efficiently vibrate the entire 55 screening area thereof.

Any suitable means may be provided for vibrating the supporting means for the screen clothing. In the present instance of the invention, this is accomplished by 60 means of cams beneath the supporting means which may have peripheral and lateral projections for imparting complex vibratory movements to the supporting means.

With the aforesaid and other purposes in 65 view, the character of the invention will be best understood by reference to the following description of one good form thereof shown in the accompanying drawings, 70 wherein:

Figure 1 is a vertical longitudinal section through a separator embodying the invention;

Fig. 2 is a transverse section taken on line 2—2 of Fig. 1;

Fig. 3 on an enlarged scale is a plan of the screen clothing and its supporting means, a portion of the former being broken away more clearly to disclose the latter;

Fig. 4 on an enlarged scale is a section 80 taken on line 4—4 of Fig. 3;

Fig. 5 is an end view of the construction shown in Fig. 3;

Fig. 6 is a perspective view illustrating a step in the manufacture of the table; and 85

Fig. 7 is a perspective view of a portion of the table showing the appearance of the bottom thereof.

Referring to the drawings, the separator shown therein as one good form of the invention, comprises a casing 1 having a cover 3 connected by hinges 5 with the casing adjacent the upper end thereof. Mounted on the top of the casing is a feed box 7 containing a screw conveyor 9 for feeding the 95 materials along the feed box and over the feed board 11 suspended by hangers 13 which may be adjusted to vary the elevation of the feed board with respect to the bottom of the feed box as desired. Beneath the 100 feed box is an inclined spill board 15 for guiding the materials flowing over the feed board into the upper end of the casing 1.

The supporting means for the screen, in the present instance of the invention, comprises a table, plate or apron 17 which may desirably be formed of a plurality of sections 19, 21 and 23 (Fig. 3). Each of these sec-

tions may be formed of a sheet metal body 25 having depending flanges 27 and 29 at the sides and ends thereof respectively. The body of the plate may have apertures 31 therein conveniently died out of the plate, so that strengthening flanges 33 may be provided depending from the body of the plate, and preferably surrounding the apertures. In the present instance of the invention, the 10 apertures are formed so as to present inwardly extending curved portions or projections 35, the construction being such that when these portions or projections are bent downward from the plane of the body 25 from the position shown in Fig. 6 to their 15 position shown in Fig. 7, they will afford strong, truss-like strengthening elements for the body 25. These strengthening elements at the edges of the apertures, and the depending side and end flanges 27 and 29 of the plate efficiently strengthen the plate and enable the same to support heavy weights.

The sections 19, 21 and 23 formed as described, may be assembled so that the flanges 29 of adjacent sections may abut against each other and constitute a continuous table or support substantially as shown in Fig. 3. The flanges 29 may be bolted or otherwise secured together, thereby enabling ready 30 substitution of new sections for old sections if required.

Projecting upward from the opposed longitudinal edges of the table, are side plates 37 rising a substantial distance above the plane of the table. These side plates 35 may serve to stiffen the sides of the table, to prevent materials flowing downward along the screen from escape over the side edges thereof, and may also serve as convenient means for detachable connection with the screen mounted on the table, as more fully hereinafter described.

Screens of varying character may be mounted on the table described. In the 45 present instance of the invention, a screen is shown comprising screen clothing 39 which may be of fine or coarse character. In the present instance, the clothing is formed of woven bronze wire of fine mesh, 50 having its margins tacked or otherwise secured to side members or bars 41 of wood or other suitable material, in the present instance, detachably secured to the side plates 37 by bolts 43, the construction being such 55 that the clothing rests upon the longitudinal and cross bars afforded between the apertures of the table described. The adjustment of the side members 41 is such that the wires of the clothing are not stretched, and 60 the meshes of the clothing are not enlarged, but the clothing rests on the table without distortion thereof or loss of the original meshes of the clothing.

Having described the supporting table 65 and the screen resting thereon, next will be

described means for supporting the table. This means, in the present instance of the invention, comprises longitudinal members or channels 45 preferably extending the length of the table. Mounted on these channels are transverse members 47 having edge portions 49 secured to the backs of the channels, and free portions projecting or inclined upward from the secured edges so as to present curved marginal portions 51. The ends of these curved marginal portions may be bolted or otherwise secured to the screen supporting table. The construction is such that the longitudinal channels may flex in the direction of the length thereof, and the members 47 mounted on and crossing the same may flex transversely and longitudinally of said members. Therefore, the channels and cross members constitute a frame of a highly resilient character susceptible of pronounced and complex vibratory movements for efficiently vibrating the supporting table and the screen, as more fully hereinafter described.

Any suitable means may be provided for 90 vibrating this frame. To accomplish this, in the present instance, cams 53 may be provided, each preferably made in two parts so as to be readily clamped on shafts 55 which may extend across the casing 1 and 95 have end portions thereof journaled in bearings 57 mounted on angle bars 59 having their ends secured to the side walls of the casing externally thereof.

These angle bars may be of a flexible, resili- 100 ent character, such that the bearings may be susceptible of more or less movement which will further contribute to efficient vibration of the screen.

Each of the cams may have humps or 105 projections 61 on the periphery thereof, the number of which may be varied as desired. Coöperating with the peripheral humps of the cams are followers conveniently in the form of rollers 63 mounted on shafts 65 110 carried by the depending flanges of the channels 45. The construction is such that on rotation of the cams, the humps thereof will progressively engage and thump the rollers, and thereby vibrate the screen sup- 115 porting frame and table. Preferably the cams are rotated out of step so that the screen will be rocked laterally and longitudinally and with complex movements caused by the out of step thumpings of the 120 cams. This will cause the longitudinal channels to undulate or vibrate longitudinally with a snake-like motion, and cause the transverse members on the channels to undulate or vibrate with a snake-like move- 125 ment which will be further modified by other vibrations occasioned by the transverse curvature and resilience of the transverse members. These vibrations of the frame are in turn transmitted to the table, and since 130

the screen clothing rests upon the table, these vibrations will be transmitted from the latter to the screen. Since the screen clothing is not stretched, it will be free to 5 flap against the table throughout the area of the clothing, and thus the latter will be vigorously vibrated throughout, so that the meshes thereof will be maintained in open condition for efficient grading effect.

10 Portions of the clothing will strike the longitudinal and transverse bars afforded between the apertures in the table, but the clothing will not be objectionably injured thereby, owing to the rounded character of 15 said bars as they merge into their depending strengthening flanges. Also, the bars will not offer material obstruction to or reduce the effective screening area of the clothing, since the materials being graded 20 may pass through the meshes of the clothing above said bars while the clothing is flapping up away from said bars, the transverse curvature of the latter serving to desirably deflect the materials flowing through 25 the clothing to the apertures in the table.

In some instances it may be desirable not only to provide the cams with peripheral projections, but also to provide the same with lateral projections for imparting lateral shaking movements to the frame, table and screen. In the present instance, the cams are provided with lateral knobs or projections 67 adapted to engage followers, in the present instance, in the form of 30 wedges 69 secured to depending flanges of the channels 45. The construction is such that on rotation of the cams, the lateral projections will engage and thump against the wedge followers 69 and impart lateral shaking movements to the screen.

The cams may be so located as to support the screen in inclined position, in order that the materials delivered by the spill board 15 referred to, may flow downward along the 45 screen. Suitable means may be provided for preventing the screen from sliding downward off from the cams. This means, in the present instance, comprises hanger rods 71 (Fig. 1) having their upper ends entered 50 through holes in the upper end of the casing and provided with adjusting and lock nuts 75. At the lower end of the hanger rods are chains 77 connected to bolts 78 attached to the channels.

55 The tendency of the cams in the course of their rotation is to thrust the frame, table and screen upwardly if the cams are rotated in a clockwise direction (Fig. 1). Suitable means may be provided yieldingly to oppose 60 such movement. This means, in the present instance, comprises rods 79 having ends attached to the frame, and portions extended through brackets 81, coil springs 82 being mounted on said rods and confined between 65 said brackets and nuts on said rods. The

construction is such that the springs will react against the brackets and operate through the rods to yieldingly draw the frame downward until limited by the hanger and chains referred to. 70

The cover may have curtains or plates 83 (Fig. 2) depending therefrom and co-operating with the plates 87 referred to, to prevent escape of materials over the sides of the screen. 75

In operation, the materials to be graded are introduced into the feed box 7 and fed by the conveyer screw 9 along the same. The materials will flow over the feed board 11, gravitate downward to the spill board 15, 80 and be deflected by the latter onto the upper end of the screen. They will flow downward along the screen, and the coarser materials will be delivered to an opening 85 communicating with an opening in the bottom of the casing, while the fines will pass through the screen into the chamber 87 and be delivered through another opening in the bottom of the casing. The screen will be vigorously vibrated by the means described 90

so as to maintain the meshes of the clothing in open condition for efficient grading effect. The flanges of the channels will desirably protect the cams and their rollers from the materials flowing downward past the same, 95 and thus the cams and rollers will be protected from the abrading effect which would occur if the materials were allowed to fall thereon. The channels will not reduce the efficient area of the screen, since they are 100 located a substantial distance beneath the plane of the screen, and materials passing through the screen striking the backs of the channels may readily flow off from the same. Also, the transverse members 45 will not reduce the effective screening area of the 105 clothing, since any materials striking said members may readily flow off from the same.

The cover 3 of the casing may be readily opened when it is desired to expose the 110 screen clothing for purposes of inspection, adjustment or repair thereof, and the entire area of the clothing is without obstruction so that materials thereon may be readily swept therefrom if desired, although there 115 is little occasion for sweeping the materials from the clothing, owing to the efficient vibration thereof, which keeps the meshes of the clothing always in open condition.

The screen, table and supporting frame 120 may be readily removed from the casing as a unit if desired. To accomplish this, it is merely necessary to release the hangers 71 and 79 thereby allowing the supporting frame to be readily disconnected therefrom 125 and lifted off from the cams out of the casing.

Since the screen clothing is connected to its support by the side members extending longitudinally of the clothing, the ends of the 130

screen clothing are not obstructed by frame members, and the materials to be graded may readily flow along the clothing without hindrance. When it is desired to substitute new clothing for old clothing, it is merely necessary to release the bolts 43 from the side plates 47, thereby permitting the clothing to be quickly and easily lifted from the table. Then new clothing may be mounted on the 10 table, and the side members thereof may be easily and readily bolted to the side plates, and the change will be effected with a minimum loss of time.

The apertures in the table may be variously disposed, but preferably they are in staggered relation, the construction being such that any materials falling on the curved bars between the apertures, if not deflected laterally thereby through the apertures, will 20 flow along the longitudinal bars and be directed to the next adjacent apertures. As a consequence, the finer materials passing through the screen clothing will be sure to flow readily through the apertures in the 25 table.

In some cases it may be desirable to provide a screen beneath the screen described, further to grade materials. The perforated plate having the depending strengthening 30 flanges desirably coöperates with the lower screen, since the material passing through the apertures may strike the depending flanges and be checked in its descent so as to be desirably distributed to the lower screen 35 and fall with substantially equal velocity and thereby contribute to equal secondary gradation of the material.

It will be noted that the frame, table and screen are supported on the cams independently of the casing, and that the screen is not connected to or stretched between the side walls of the casing. As a consequence, the frame, table and screen are susceptible of bodily movement relatively to the casing 45 when thumped by the supporting cams. This produces a pronounced vigorous vibration of the screen, materially more effective in keeping the meshes of the clothing in open condition than if the screen were connected 50 to the walls of the casing.

It is desirable that the apertured table shall be connected to the ends only of the curved resilient transverse bars 47, so that the portion of the table between the margins 55 thereof thus secured may slap up and down against the transverse bars and against the clothing above the table. The cam humps acting out of step on the channels will impart a great variety of vibrations to the 60 resilient channels and transverse bars and thence to the table and clothing. The channels will have up and down and lateral undulatory movements and reciprocatory movements in the direction of the length of the 65 channels. The transverse bars will have up

and down undulatory movements and reciprocatory movements in the direction of the length thereof. Since the transverse bars are connected to the backs of the channels at points substantial distances in from the ends 70 of the transverse bars, flexion of the latter will cause the ends of the bars to move up and down with desirable amplitude of movement, and these movements in turn will be transmitted to the margins of the table secured thereto. As a consequence, the frame, 75 table and clothing are so vigorously shaken that the meshes in the clothing cannot be clogged, but on the contrary are maintained open for efficient grading effect.

By my invention is provided a separator which is simple and strong in construction, cheap to manufacture, and not liable to get out of order. It is capable of efficiently 80 grading a great variety of materials with 85 rapidity of operation, and indeed the character of the vibration obtained by the means described is such that certain materials of adhesive or sticky character which hitherto could not be graded, may be readily 90 screened by this separator.

It will be understood that the invention is not limited to the specific embodiment shown, and that various deviations may be made therefrom without departing from the 95 spirit and scope of the appended claims.

What is claimed is:—

1. A separator for grading materials, comprising, in combination, a frame including channels and transverse members connected 100 to said channels, a table of sheet material mounted on said frame having a multiplicity of perforations therein with strengthening flanges depending from said perforations, side plates secured to said table, a screen secured 105 to said side plates and having clothing resting on said apertured table, and means operating through said frame and table for causing the clothing to slap against said table and maintain the meshes of the clothing 110 in open condition.

2. A separator for grading materials, comprising, in combination, a table having marginal strengthening flanges and apertures having marginal strengthening flanges 115 with rounded ribs between the apertures, and a screen having clothing resting on the rounded ribs, and means for causing the clothing to slap against said ribs and thereby maintain the meshes of the clothing in 120 open condition.

3. A separator for grading materials, comprising, in combination, a table formed of sections having marginal flanges secured together, each of said sections having apertures therein with marginal flanges depending from said apertures, a screen having clothing resting on said table, and means to shake the table and clothing and cause the latter to slap against the former and 125 130

maintain the meshes of the clothing in open condition.

4. A separator for grading materials, comprising, in combination, a table having a multiplicity of apertures therein provided with marginal truss flanges to strengthen the table, a screen having clothing resting on the table, and means to shake the table and cause the clothing to slap against the same to maintain the meshes of the clothing in open condition.

5. A separator for grading materials, comprising, in combination, a sectional plate having a multiplicity of flanged holes punched therein, a screen having side members secured to said plate and clothing extending over said plate between said side members and resting on said plate without tension, and means to shake said plate and cause said clothing to slap against the same to keep the meshes of the clothing in open condition.

6. A separator for grading materials, comprising, in combination, a table formed of sheet material and having a multiplicity of apertures punched therein in staggered relation, a screen having clothing resting on said table, and means beneath said table for supporting it in an inclined position and operable to shake said table and cause the clothing to slap against the table and keep the meshes thereof in open condition.

7. A separator for grading materials, comprising, in combination, a frame, means for supporting and energetically shaking the frame, a sheet metal apron carried by said frame having a multiplicity of apertures therein, and a screen having clothing resting on said table and vibrated thereby.

8. A separator for grading materials, comprising, in combination, a frame provided with transverse resilient bars arranged at spaced intervals, a perforated apron of sheet material extending over said bars and supported thereby, screen clothing resting upon said apron, and means for energetically vibrating said frame to produce vibrations in the transverse bars and to impart said vibrations to the apron and screen clothing to cause the clothing to slap against the apron.

9. A separator for grading materials, comprising, in combination, a frame comprising channels, cross members mounted on said channels, an apertured plate mounted on said cross members, a screen having clothing resting on said plate, and means operating through said frame for shaking the table and screen, said apertured plate being substantially coextensive with the clothing resting thereupon.

10. A separator for grading materials, comprising, in combination, an inherently resilient frame, a perforated sheet metal apron extending over the frame and carried thereby, a screen having clothing resting on said apron, and means to vibrate said frame to cause the apron and clothing to slap against each other and maintain the meshes of the clothing in open condition.

11. A separator for grading materials, comprising, in combination, an inherently resilient frame including longitudinal members and transverse members secured across the longitudinal members at spaced intervals, a perforated sheet metal apron extending over the frame and secured thereto, a screen having clothing resting on said apron, and means for energetically vibrating the frame to shake the same and produce local vibrations within the frame and within the apron and clothing and to cause the clothing to slap against each other and maintain the meshes of the clothing in open condition.

12. A separator for grading materials, comprising, in combination, an inherently resilient frame including channels and transverse members connected to the channels, a table of sheet metal carried by said frame and having a multiplicity of perforations therein, a screen having clothing resting on the table, and means for energetically vibrating the frame to shake the same and produce local vibrations within the frame and within the apron and clothing and to cause the clothing to slap against each other and maintain the meshes of the clothing in open condition.

In testimony whereof, I have signed my name to this specification.

THOS. L. STURTEVANT.
